UNITED STATES PATENT OFFICE

HARVEY A. JETMORE, OF LAWRENCE, KANSAS.

TOURIST'S CABINET.

Application filed February 11, 1927. Serial No. 167,537.

The present invention is directed to improvements in tourists' cabinets, for use in connection with automobiles.

The primary object of the invention is to provide cabinets of this character adapted to be fixed to the running board of an automobile, the construction being such that provision is made for maintaining articles of food in a cool state. Further, it is one of the objects of the invention to provide a cabinet of this nature wherein a camper's outfit can be compactly and conveniently stored.

Another object of the invention is to provide a device of this character capable of being easily and quickly attached to or removed from the running boards of a motor vehicle.

In the accompanying drawings:

Figure 1 is a top plan view of the motor vehicle, showing the cabinets in place thereon.

Figure 2 is a sectional view on line 2—2 of Figure 1.

Figure 3 is a sectional view on line 3—3 of Figure 1.

Figure 4 is a sectional view on line 4—4 of Figure 2.

Figure 5 is a sectional view on line 5—5 of Figure 3.

Figure 6 is a sectional view on line 6—6 of Figure 4.

Referring to the drawings, 1 designates a motor vehicle and 2 and 3 the right and left hand side running boards thereof. Two cabinets 4 and 5 are used, one for engagement with the right side running board and the other with the left side running board of the car, and since the cabinets are identical in construction, the description of one will suffice for both. Each cabinet comprises a back wall 6, end walls 7, top 8, and front closure 9 connected to the top by hinges 10, thus forming bottomless cabinets. The lower edges of the closures 9 are formed with recesses 11, the purpose of which will be later explained. Cross bars 12 are provided and are arranged in pairs, the bars of each pair having their rear ends fixed to the rear wall 6 and having their ends fixed to the cross bar of each pair are transversely disposed saddles 13. These

saddles are formed from strap metal and are bent to provide flanges 13' adapted to be secured upon the cross bars 12, the depressions 14' of said saddles fitting snugly between said bars, as clearly shown in Figure 2 of the drawings. The cabinets are placed upon the running boards and U-shaped clamps 14 are employed for firmly holding the cabinets in place thereon. These clamps are arranged with their upper arms 15 engaged in the recesses 11 of the closures 9 and fits in the depressions 14' the saddles 13, the lower arms 16 of said clamps being engaged under the running boards 2. A set screw 17 is carried by the arm 16 and is impinged against the lower side of the running board and serves to maintain the clamps in fixed relationship upon the running board, said clamps also serving to hold the cabinets firmly in place.

The front end of each cabinet 4 and 5 is provided with a platform 18, which forms, in effect, a continuation of the tops 8.

Removably mounted upon the platform 18 of the left hand side cabinet 5 is an auxiliary cabinet 19, which is so constructed as to provide a refrigerator for preserving articles of perishable nature, while mounted upon the platform 18 of the cabinet upon the right hand side of the running board is removably mounted an auxiliary cabinet 20. The cabinet 20 is provided with shelves 21 upon which cooking utensils are placed, said cabinet having a door 22 hingedly connected to the cabinet, as at 23. This door, as shown in Figure 5 of the drawings, may be lowered, and can be used as a table. The auxiliary cabinets 19 and 20 are so mounted upon the respective platforms that they will in no way interfere with the opening and closing of the front doors of the vehicle. It will be observed that the forward end walls 7 of the cabinet are inclined to enable the front ends of said cabinets to overhang the front fenders of the car.

To maintain the auxiliary cabinets 19 and 20 in place, the front and rear lower sides thereof are retained by pintles 24 detachably engaged with the butt leaves 25 carried, respectively by the cabinets and associated platforms 18.

The cabinet 19 is provided with a drain

opening 26 for letting water therefrom and is further provided with a holder 27 for supporting a canteen or the like.

Having thus described the invention, I claim:

The combination with the running boards of an automobile, of cabinets having laterally spaced cross bars secured thereto adapted to rest upon the running boards, saddles

including flanges for attachment to the cross bars, and having depressions formed intermediate the flanges for engagement between said bars, and clamps engaged with the running boards and including arms to engage in the depressions to maintain the cabinets upon the running boards.

In testimony whereof I affix my signature.

HARVEY A. JETMORE. [L. S.]
